UNITED STATES PATENT OFFICE.

DYCKE H. REIMERS, OF CHICAGO, ILLINOIS, ASSIGNOR OF ONE-THIRD TO DONALD W. DAVIDSON AND ONE-THIRD TO MATHIAS WEBER, BOTH OF CHICAGO, ILLINOIS.

WATER-COOLING SYSTEM FOR HYDROCARBON-ENGINES AND THE LIKE.

1,191,614.

Specification of Letters Patent. Patented July 18, 1916.

Application filed January 8, 1915. Serial No. 1,110.

To all whom it may concern:

Be it known that I, DYCKE H. REIMERS, a citizen of the United States, and a resident of the city of Chicago, in the county 5 of Cook and State of Illinois, have invented certain new and useful Improvements in Water-Cooling Systems for Hydrocarbon-Engines and the like; and I do hereby declare that the following description of my 10 said invention, taken in connection with the accompanying sheet of drawings, forms a full, clear, and exact specification, which will enable others skilled in the art to which it appertains to make and use the same.

15 This invention relates generally to improvements in a water cooling system for hydro-carbon engines and the like, and it consists, essentially, in the novel and peculiar combination of parts and details of 20 construction, as hereinafter first fully set forth and described and then pointed out in the claims.

In the drawing already referred to, which 25 serves to illustrate my said invention more fully, Figure 1 is a side elevation of a hydro-carbon engine with my improvement applied thereto. Fig. 2 is a front elevation of the radiator of a hydro-carbon engine showing more in detail some of the features of 30 the invention. Fig. 3 is a front elevation similar to that shown in Fig. 2 showing a modified construction. Fig. 4 is a vertical section taken along line *a—a* of Fig. 3.

Like parts are indicated by corresponding 35 characters and symbols of reference in all the figures of the drawing.

The object of my invention is the production of a water cooling system for hydro-carbon engines of automobiles and the like, 40 and which can, if desired, be positioned at any desirable place with reference thereto, and consists primarily in forcing cold air into the water to cause it to act as a cooling medium before it enters the water jacket 45 of the engine.

To better understand the details of the preferred embodiment of my invention, I now refer to the drawings in which the numeral 10 designates the engine as a whole, 50 from the casing 11 of which lead the inlet and outlet water conduits 12 and 13. The opposite ends of these conduits are suitably connected to the radiator 16 as indicated at 14 and 15. Interposed between the extremities of the conduit 13 as it leads from the

radiator 16 and to the casing 11 of the engine, a pump 17 is positioned, which conveniently serves as a means for positively forcing the water to circulate through the radiator and the engine casing 11. The 60 pump 17 is driven in any suitable manner and as shown is connected to the magneto shaft indicated at 18. A thermometer 19 may be utilized to apprise the operator of the mean temperature of the water in its 65 circulator, the thermometer being connected to the conduits 12 and 13 by means of the pipe 20.

To one end of the magneto shaft 18 and preferably remote from the pump 17, a 70 sprocket wheel 21 is suitably connected, and which through the medium of the sprocket chain 22 and the sprocket wheel 23 of the air pump or blower 24, conveniently serves as a means for operating said pump or 75 blower. An air pipe 25 leads from the pump 24 and is suitably connected to the manifold 26 which is preferably incased within the radiator 16, which is suitably formed to produce a chamber, within which 80 the manifold 26 is conveniently mounted. From this manifold 26 depend a series of perforated pipes 27, which are completely immersed in the water contained in the radiator, the perforations 29 serving as a 85 means by which cold air is permitted to be forced into the water by the air pump 24 to reduce the temperature thereof before again entering the water jacket of the engine casing. 90

The air pipe 25 is suitably provided with the butterfly valve 30 to regulate the amount of cold air which is forced into the water by the pump 24. This valve may be either manually or thermostatically controlled as 95 found most desirable and convenient. The means herein shown consists of the rod 31 which has its opposite ends connected to the lever 32 and the adjusting mechanism 33, respectively, which is adapted to regulate 100 and secure the valve 30 in its proper adjusted position.

The radiator 16 is further provided with the filling plug 34 and also with the aperture 35 which serves as a convenient air intake for the air pump 24. 105

In the construction of the device as shown in Figs. 3 and 4, the manifold 26 is positioned at the bottom of the radiator chamber and the perforated pipes 26 are horizon- 110

tally disposed in contradistinction to the form shown in Fig. 1 in which the pipes are illustrated as being vertically disposed.

It will be evident that the radiator can 5 without any inconvenience be positioned at any desirable place upon or within the car as, for instance, underneath the seat or any other place found convenient, as the cooling of the water does not depend upon any element other than the one herein shown and 10 described.

I now call attention to the fact that the thermometer 19 is a part of the water circuit and that by observing the temperature 15 of the circulating water, the operator is in position to so regulate the temperature of the circulating water by manipulating the valve 30, that by experiments conducted with the object in view, he can keep this 20 circulating water at a predetermined temperature which will give the best results in the operation of the motor 10. This feature of 25 my invention is a very important one, resulting in increased efficiency of the motor and producing other desirable results.

I have heretofore stated that the pipes in the radiator are preferably perforated by a series of comparatively small holes; but I desire it understood that otherwise shaped 30 openings may be resorted to without departing from the scope of my invention.

While I have herein shown and described the preferred method of practising my invention, I reserve the right to make such 35 changes and alterations as would suggest themselves to the skilled mechanic or permitted under the doctrine of equivalents.

Having thus fully described my invention I claim as new and desire to secure to myself by Letters Patent of the United 40 States:—

1. In combination, a radiator possessed of 45 inlets thereinto and outlets therefrom, an air impeller fixed to said radiator, receiving its supply of air through said radiator from exteriorly thereof and discharging said air into said radiator, and means for operating said impeller.

2. In combination, a radiator possessed of 50 inlets thereinto and outlets therefrom, an air impeller fixed to said radiator, receiving

its supply of air through said radiator from exteriorly thereof and discharging said air into said radiator in a diffused condition, and means for operating said impeller. 55

3. In combination, a radiator possessed of inlets thereinto and outlets therefrom, an air impeller fixed to said radiator, receiving its supply of air through said radiator from exteriorly thereof and discharging said air 60 into said radiator, and means for operating said impeller, there being means controlling the flow of said air into said radiator.

4. In combination, a radiator possessed of inlets thereinto and outlets therefrom, an 65 air impeller fixed to said radiator, receiving its supply of air through said radiator from exteriorly thereof and discharging said air into said radiator in a diffused condition, there being means controlling the flow of 70 said air into said radiator.

5. In combination, a radiator possessed of inlets thereinto and outlets therefrom, of a cylindrical hollow member located in said radiator, in its upper portion, horizontally, 75 and substantially of its length thereof, a plurality of perforated hollow members depending from said horizontal member, an air impeller fixed to the exterior of said radiator and constructed to discharge air into 80 said horizontal member, whereby air in a diffused condition is discharged within said radiator, and means for operating said impeller.

6. In combination, a radiator having inlets and outlets, of a longitudinal, cylindrical, hollow member in said radiator, a plurality of equally spaced, perforated, hollow members extending from said longitudinal member, an air impeller in connection with 90 said radiator and means actuating the same, said impeller being constructed to discharge air into said longitudinal member, whereby air in a diffused condition is discharged within said radiator. 95

In testimony whereof I have hereunto set my hand in the presence of two subscribing witnesses.

DYCKE H. REIMERS.

In the presence of—

W. HARDING,
C. S. STARK.
